Specification for Design.

Patented Aug. 27, 1918.

Application filed June 21, 1918. Serial No. 241,297. Term of patent 14 years.

To all whom it may concern:

Be it known that I, ARTHUR L. BREITENSTEIN, a citizen of the United States, and resident of Akron, county of Summit, and State of Ohio, have invented a new, original, and ornamental Design for a Tire-Casing, of which the following is a specification, reference being had to the accompanying drawing, forming part thereof.

In said annexed drawing:

Figure 1 is a plan view; Fig. 2 is a sectional view; and Fig. 3 is a side elevation of a portion of a tire casing, showing my new design.

I claim:—

The ornamental design for a tire casing as shown.

Signed by me, this 17th day of June, 1918.

ARTHUR L. BREITENSTEIN.
